UNITED STATES PATENT OFFICE

CHESTER W. CRUMMINE, OF ROCHESTER, NEW YORK, ASSIGNOR TO ELECTROMATIC TYPEWRITERS, INC., OF ROCHESTER, NEW YORK, A CORPORATION OF NEW YORK

PAPER FEED ROLLER

Application filed September 11, 1930. Serial No. 481,915.

This invention relates to improvements in rollers, and particularly to that kind of rollers used for feeding paper rolls or perforated sheets in power driven typewriting machines or perforating machines in which means are provided at the ends of the roller for positively engaging the sheet to be fed. Such rollers are usually provided with circumferentially arranged studs or projections at their ends which are adapted to engage perforations arranged along the side edges of the sheet. Since the width of the sheet varies with atmospheric conditions which affect its temperature and moisture content, unless such conditions are nearly uniform, the perforations at one side of the sheet fail to register with the projections on the roller, or the sheet buckles between its ends, and its perforations which control the machine fail to register exactly with the parts to be controlled thereby. To overcome this difficulty, it has been proposed to provide the projections at one end of the roller on an axially movable part which would readily adjust itself to the width of the sheet, but by this means the whole expansion or contraction of the sheet moves in one direction since the other end is fixed, with the result that the control perforations near the movable end sometimes fail to register.

The object of this invention is to provide simple and inexpensive means for moving the projections at opposite ends of the roller equal distances laterally so that the expansion or contraction of the sheet is evenly distributed on opposite sides of the middle of the roller.

Another object of the invention is to provide a roller of this kind in which the sheet engaging projections at the ends of the roller are connected by means arranged within the roller for moving them equal distances toward or from each other.

To these and other ends, the invention consists in the construction and arrangement of parts that will appear from the following description when read in conjunction with the accompanying drawing, the novel features being pointed out in the claims at the end of the specification.

In the drawing:

Fig. 1 is a longitudinal section of a feed roller illustrating one possible embodiment of the invention;

Fig. 2 is an end elevation of the same;

Fig. 3 is a transverse section taken substantially on line 3—3 of Fig. 1, and

Fig. 4 is a section taken on line 4—4 of Fig. 2.

Referring particularly to the drawing, in which like reference numerals refer to the same part in all the views, 1 represents the body portion of a roller, which in the present embodiment is hollow and may be constructed of suitable material, and, if desired, provided with circumferentially arranged depressions or grooves 2 adapted to cooperate or register with openings or perforations in a master sheet arranged thereon.

Arranged in each end of the body to turn therewith are hollow cores or sleeves 3 and 4, and spaced from the sleeve 4 is a second sleeve 5, and secured in the sleeves 4 and 5 and projecting from the end of the roller is a tubular member 6 in which a stub shaft 7 is mounted. The stub shaft 7 is mounted at its inner end in a bushing 8 and extends through the tubular member 6 and is mounted in the frame by means of the lock nuts 9.

Mounted on the tubular member 6 and slideable thereon to and from the end of the body 1 is a ring 11 having circumferentially arranged studs or projections 12 adapted to engage perforations provided therefor at the side of the sheet to be fed. Fixed in this ring to move therewith and arranged substantially parallel to the axis of the roller are the rods or shafts 13 and 14. The rods or shafts 13 and 14 are secured to the ring by any suitable or preferred means, such as the nuts 10 shown in the drawing, and they extend inwardly from the ring diametrically opposite each other. At their inner ends the rods 13 and 14 operatively engage the ends of levers 15 and 16 pivoted intermediate their ends on headed screws 17 and 18 threaded in diametrically opposite tapped openings in the tubular member 6. The opposite ends of the levers 15 and 16 operatively engage rods or shafts 19 and 20 which extend longitudinally

through the roller and have a ring 21 secured thereto at their outer ends by any suitable or preferred means, such as the nuts shown. The ring 21 is similar to the ring 11 arranged at the other end of the roller and is adapted to move axially of the roller to and from its end with the rods 19 and 20 and having the studs or projections 22 adapted to engage perforations arranged along the other side of the sheet.

By this arrangement, movement of either of the rings 11 or 21 toward or from the end of the body is communicated equally to the other of said rings through the levers 15 and 16 and the rods connected therewith. The rings 11 and 21 are hence readily adjusted to the width of the sheet and automatically adjust themselves thereto, such adjustment being substantially equal in opposite directions from the middle of the sheet so that perforations or other matter appearing on the sheet receive but slight lateral displacement on the roller.

The sleeve or collar 3 mounted in the end of the roller projects laterally therefrom to provide a support 23 on which the ring 21 is slidably mounted.

Although only one embodiment of the invention is shown and described herein, it will be understood that this application is intended to cover such changes or modifications as come within the spirit of the invention or scope of the following claims, and although a roller for feeding a master sheet is described, a roller thus constructed will be found useful wherever sheets are to be positively fed by means of rollers.

I claim:

1. A sheet feeding roller for typewriting machines or the like comprising a cylindrical body portion, a ring arranged at each end of said body portion and movable toward and from the ends thereof, means operatively connecting said rings for imparting simultaneous movement thereto, and means on said rings for positively engaging a work sheet.

2. A sheet feeding roller for typewriting machines or the like comprising a hollow cylindrical body portion, a ring arranged at each end of said body portion and movable toward and from the ends thereof, a rod projecting inwardly from each of said rings, means operatively connecting the inner ends of said rods for moving the rings simultaneously in opposite directions, and means on the rings for positively engaging a work sheet.

3. A sheet feeding roller for typewriting machines or the like comprising a hollow cylindrical body portion, a ring arranged at each end of said body portion and movable toward and from the ends thereof, a lever pivoted in said body portion, means operatively connecting the opposite ends of said

lever with said rings, and means on said rings for positively engaging a work sheet.

4. A sheet feeding roller for typewriting machines or the like comprising a hollow cylindrical body portion, a ring arranged at each end of said body portion and movable toward and from the ends thereof, a lever pivoted in said body portion and arranged to swing in a plane parallel with its axis, a rod operatively connecting each end of said lever with one of said rings, and means on said rings for positively engaging a work sheet.

5. A sheet feeding roller for typewriting machines or the like comprising a hollow cylindrical body portion, a ring arranged at each end of said body portion and movable toward and from the ends thereof, a pair of levers pivoted in said body portion and arranged to swing in planes parallel with its axis, a pair of rods secured to each of said rings at one end and operatively connected with said levers at their other ends, and means on said rings for positively engaging a work sheet.

6. A sheet feeding roller for typewriting machines or the like comprising a hollow cylindrical body portion, a ring arranged at each end of said body portion and movable toward and from the ends thereof, a support secured in said body portion, a plurality of levers pivoted on said support, a pair of rods corresponding to each of said levers one secured in each of said rings and operatively connected with opposite ends of one of said levers, and means on said rings for positively engaging a work sheet.

7. A sheet feeding roller for typewriting machines or the like comprising a hollow cylindrical body portion, a ring arranged at each end of said body portion and movable toward and from the ends thereof, a pair of levers having arms of equal length, rods connecting one arm of each of said levers with one of said rings and the other arms with the other of said rings, and means on said rings for positively engaging a work sheet.

In witness whereof I have hereunto signed my name.

CHESTER W. CRUMRINE. 115
